UNITED STATES PATENT OFFICE

CARL E. JOHNSON, OF LOS ANGELES, CALIFORNIA, ASSIGNOR TO UNITED STATES ELECTRICAL MANUFACTURING COMPANY, OF LOS ANGELES, CALIFORNIA, A CORPORATION OF CALIFORNIA

WEATHERPROOF PUMP MOTOR

Application filed September 15, 1926. Serial No. 135,671.

This invention relates to electric motors and particularly to turbine irrigation pump head constructions.

In the past and at the present time it is ordinary practice to protect the pump head of a turbine irrigation pump by enclosing it in a small pump house. It is the tendency however to do away with the pump house in order to decrease expenses, this subjecting the pump head to the rain, sun and other elements. It is very important that the driving motor of the pump head be protected from the elements, especially from rain and moisture which are capable of doing considerable damage to the windings of the motor.

It is an object of this invention to provide a pump head construction for turbine irrigation pumps in which the motor is adequately protected from the elements.

It is quite essential that the motor have ample ventilation and therefore any protective means for the motor must be designed to permit proper ventilation.

It is accordingly an object of this invention to provide a protector for motors which permits adequate ventilation.

Other objects and advantages of the invention will be made evident hereinafter.

Referring to the drawings in which I illustrate the invention,

Fig. 1 is a small diagrammatic view illustrating a utility of the invention.

Fig. 2 is an enlarged section taken through a preferred form of the invention.

Fig. 3 is a section taken on the line 3-3 of Fig. 2.

Fig. 4 is a section taken on the line 4-4 of Fig. 2.

Fig. 5 is a vertical section taken through a second form of the invention.

Referring to the drawings and particularly to Fig. 1, the numeral 11 represents a pump head which is mounted at the upper end of a well 12. Placed in the well 12 near the lower end thereof, below the water level,

is a pump section 13. The pump section 13 is attached to the lower end of a discharge pipe 14 which extends upward through the well 12 to the surface of the ground where it is connected to the pump head 11. The pump head 11 consists of a body 16, to the interior of which the discharge pipe 14 is connected, and a drive means in the form of a motor 17. The motor 17 as shown in Fig. 1 is provided with a protective jacket 18 embodying the features of the invention.

Referring to Figs. 2 to 4 inclusive, the details of the invention will be described. The motor 17 consists of a lower frame 20 which is supported by the body 16. Resting on a shell portion 21 of the lower frame 20 and secured thereto by bolts 22 is a stator 23. Supported by the stator 23 is an upper frame 25 which is attached thereto by bolts 26. The lower frame 20 has a bearing chamber 27 in which a bearing 28 is supported and the upper frame 25 has a bearing chamber 30 in which an upper thrust bearing 31 is supported, the bearing chamber 30 being defined by walls 32 of the upper end of the upper frame 25. Extending through the bearing chambers 27 and 30 is a pump shaft 33 which extends from the pump head 11 to the pump section 13 in the well 12. Situated in an opening 34 of the stator 23 is a rotor 35. The rotor 35 is secured on a quill 36 which surrounds the shaft 33 as shown. The upper end of the quill 36 is attached to a thrust block 38 as shown so that the thrust block will be driven by the rotor 35 through the quill 36. The thrust block 38 is supported by the thrust bearing 31 and is drivably attached by a nut 39 to the shaft 33.

The walls 32 of the upper end of the frame 25 are closed by a cover member 40 which is secured in place by bolts 42. The cover member 40 has an annular downward extending rim 43 which defines the upper end of the bearing chamber 30 and prevents the entrance of any water thereinto. Completely

surrounding the motor 17 with the exception of the extreme lower part of the lower frame 20 is the jacket 18. The jacket 18 has a cylindrical portion 45 which completely encloses the motor with the exception of the extreme upper end thereof. A radial wall 46 is formed at the upper end of the cylindrical portion 45, this radial wall 46 being annular and extending inward. The top frame 25 is provided with a shell portion 48 having flat faces 49 where the bolts 26 extend therethrough, and on these flat faces 49 the jacket 18 is supported by engagement of the lower face of the radial wall 46 therewith. Extending upward from the inner edge of the radial wall 46 is an annular flange 50. The upper end of the annular flange 50 projects inside the rim 43, terminating slightly above the lower edge thereof. The motor 17 is entirely protected from the sun since the enclosure consisting of the rim 43 and the jacket 18 is complete. The motor 17 is protected from moisture and rain by reason of the fact that there are no upward directed openings through which moisture or rain may pass in order to enter the motor. There are however openings which provide a thorough and efficient ventilation for the motor.

Referring to Fig. 2, air may enter the lower part of the motor through openings 55 formed in the shell 21 as indicated by the arrow 56, being circulated by a lower fan 56a. The air may circulate through the motor and pass from the interior thereof as indicated by the arrows 57. Air is also drawn inward at the upper end of the motor by an upper fan 58, as indicated by arrows 59, the air passing through openings 60 in the upper shell. The air flows outward from the motor as indicated by arrows 61. The lower end of the cylindrical portion 45 of the jacket 18 is open so that air may move downward inside of it as indicated by the arrow 62.

In Fig. 5 I illustrate a form of my invention having a secondary jacket 70. In this form of the invention the cylindrical wall 45 of the jacket 18 may be shortened as shown.

From the foregoing description the advantages of the invention are obvious. The jacket 18 assisted by the rim 43 provides complete protection from the elements. These parts are so constructed that a thorough ventilation may be established even though the motor is entirely protected from the elements. The invention eliminates the necessity for a pump house and is decidedly cheaper. The cost of the jacket 18 and of providing the rim 43 on the cover 40 is considerably less than the cost of the usual pump house.

I claim as my invention:

1. In combination: a stator; a rotor inside said stator; means for supporting said rotor;

a frame for supporting said stator; a weather-proof cover attached to the upper end of said frame and covering said means for supporting said rotor, said cover having an annular rim; a jacket supported by said frame, said jacket surrounding said stator and having an annular flange extending upward and terminating beneath said rim; a lower fan for drawing air inward through the lower part of said frame and forcing it outward into a space between said stator and said jacket; and an upper fan for drawing air into said motor between said flange and said frame and forcing it outward into said space between said stator and said jacket. 70 75

2. In combination: a stator; a rotor inside said stator; means for supporting said rotor; a frame for supporting said stator; a weather-proof cover attached to the upper end of said frame and covering said means for supporting said rotor, said cover having an annular rim; and a jacket, said jacket having a cylindrical portion surrounding said rotor so as to provide an annular space therearound, a radial wall resting on said frame and being secured thereto, and an annular flange extending upward from said radial wall and terminating beneath said rim. 80 85 90

3. In combination: a stator; a rotor inside said stator; means for supporting said rotor; a frame for supporting said stator; a weather-proof cover attached to the upper end of said frame and covering said means for supporting said rotor, said cover having an annular rim; a jacket, said jacket having a cylindrical portion surrounding said stator so as to provide an annular space therearound, a radial wall resting on said frame and being secured thereto, and an annular flange extending upward from said radial wall and terminating beneath said rim; a lower fan for drawing air inward through the lower part of said frame and forcing it outward into said annular space between said stator and said jacket; and an upper fan for drawing air into said motor between said flange and said frame and forcing it outward into said annular space between said stator and said jacket. 95 100 105 110

4. In combination: a stator; a rotor inside said stator; means for supporting said rotor; a frame for supporting said stator and having a closed upper end portion; a rim extending outwardly from and surrounding said closed upper end portion of said frame; and a jacket supported by said frame, said jacket surrounding said stator and having an annular flange extending upward and terminating beneath said rim. 115 120 125

5. In combination: a stator; a rotor inside said stator; means for supporting said rotor; a frame for supporting said stator and having a closed upper end portion; a rim extending outwardly from said closed upper end portion of said frame; a jacket supported by 130

said frame, said jacket surrounding said stator and having an annular flange extending upward and terminating beneath said rim; a lower fan for drawing air inward through the lower part of said frame and 5 forcing it outward into a space between said rotor and said jacket; and an upper fan for drawing air into said motor between said flange and said frame and forcing it outward into said space between said rotor and said 10 jacket.

6. In combination: a stator; a rotor inside said stator; means for supporting said rotor; a frame for supporting said stator and having a closed upper end portion; a rim extending outwardly from said closed upper end portion of said frame; and a jacket, said 15 jacket having a cylindrical portion surrounding said rotor so as to provide an annular space therearound, a radial wall resting on said frame and being secured thereto, and an annular flange extending upward from said radial wall and terminating beneath said 20 rim.

25. 7. In combination: a stator; a rotor inside said stator; means for supporting said rotor; a frame for supporting said stator and having a closed upper end portion; a rim extending outwardly from said closed upper end portion of said frame; a jacket, said 30 jacket having a cylindrical portion surrounding said rotor so as to provide an annular space therearound, a radial wall resting on said frame and being secured thereto, and an annular flange extending upward from 35 said radial wall and terminating beneath said rim; a lower fan for drawing air inward through the lower part of said frame and forcing it outward into a space between said 40 rotor and said jacket; and an upper fan for drawing air into said motor between said flange and said frame and forcing it outward into said space between said rotor and said jacket.

45. 8. In combination in a motor: a frame; a stator mounted in said frame; a rotor rotatably mounted in said frame; a cover secured to the upper end of said frame and having an annular rim thereon; and a jacket 50 secured to said frame and extending downward around said stator, said jacket having an upward extending flange terminating beneath said rim.

55. 9. In combination with a vertical-shaft motor having a stator and a rotor: a jacket extending downward around said motor, there being an annular space between said jacket and said stator which annular space is open at the bottom; a weather-proof cover 60 member providing a downward extending rim; a flange extending upward from said jacket to a point inside said rim, said rim and said flange defining a passage therebetween; means for drawing air through said 65 passage and into cooling relationship with

said motor, said air being discharged into said annular space; and means for drawing additional air into cooling relationship with the lower portion of said motor, said air being discharged into said annular space.

10. In combination in a vertical-shaft motor: a stator; a rotor mounted to rotate adjacent said stator; a cover member above said stator and providing a rim extending outward and downward; a jacket supported in spaced relationship with said stator and extending downward therearound in protecting relationship to provide an annular space between the periphery of said stator and said jacket, said annular space communicating with the atmosphere at its lower end; an annular flange associated with said jacket and extending upward beneath said rim to provide an upward directed passage, the lower end of which communicates with the atmosphere and the upper end of which communicates with the interior of said motor; and means associated with said rotor for drawing air through said upward directed passage and into cooling relationship with said rotor and stator, said air being discharged into said annular space.

11. In combination with a motor having an external surface and including a stator and a rotor: a member extending downward and around said motor and spaced from said external surface to provide an annular space therebetween, said member including a wall extending across and closing the upper end of said annular space; and cooling means for drawing air into said motor to cool said stator and said rotor and discharging said air into said annular space.

12. In combination in a vertical-shaft motor: a stator; a frame member extending across the upper portion of said stator; a rotor inside said stator; a cover member supported by said frame member and providing a rim extending outward and downward from said frame member; a jacket supported by said frame and extending downward around said stator in protecting relationship therewith; and an annular flange associated with said jacket and extending upward beneath said rim to provide an upward directed passage therebetween which communicates with the interior of said motor; and means for forcing a stream of air through said passage.

13. In combination in a vertical-shaft motor: a stator; a frame member extending across the upper end of said stator and including walls forming a bearing chamber; a shaft journaled in said bearing chamber and extending downward through said stator; a rotor on said shaft; a cover member including a rim extending outward from the upper end of said frame member; and an annular flange surrounding said walls and defining a space therebetween communicating with the interior of said motor, said an-

nular flange extending upward beneath said rim to provide an upward directed passage communicating at its lower end with the atmosphere and at its upper end with said space whereby air circulating through said space and said passage cools both the interior of said motor and said walls forming said bearing chamber.

In testimony whereof, I have hereunto set
10 my hand at Los Angeles, California, this 10
day of Sept., 1926.

CARL E. JOHNSON.
